CLOSURE

William J. Keith, Brookline, Mass., assignor to
Kep-Ark Inc., Boston, Mass., a corporation of
Massachusetts

Application October 24, 1934, Serial No. 749,738

7 Claims. (Cl. 215—43)

My invention relates to closures for bottles, flasks, jars, and other containers.

Threads upon the containers are not of uniform shape or smoothness throughout their respective lengths but contain minor defects and irregularities. Therefore in the manufacture of closures for containers it has been found that the former are rendered inadequate or useless because their imperfect fit or interengagement 10 with the threaded portions of the containers.

An object of the present invention is to insure a perfect fit of the closure upon the container regardless of the structural inequalities of the latter.

15 Additional objects of the invention are to prevent the accidental escape of the filler disk, and to insure an air tight seal between the latter and the guide ring or cylinder of the closure at their junction with each other, whereby the ingress of 20 air to, or escape of aroma from, the container is insured.

Further objects of invention are security of the assembled parts of the closure, speed and inexpensiveness of construction, and the avoidance 25 of exterior disfigurement of the closure in effecting these purposes.

With the above and other objects and advantageous features in view, the invention consists of an arrangement of parts more fully disclosed in 30 the detailed description following, in conjunction with the accompanying drawing, and more specifically defined in the claims appended thereto.

Referring to the drawing,

Figure 1 is a side elevation of a container with 35 my novel closure therefor engaged therewith,

Figure 2, a top plan view of the closure,

Figure 3, an enlarged diametrical section of the same,

Figure 4, a fragmentary side elevation of the 40 container showing in diametrical section the closure in locked engagement therewith,

Figure 5, a front elevation of the guide ring,

Figure 6, a fragmentary plan view of the front portion of the ring,

45 Figure 7, a detailed perspective view of the disk after assemblage of the parts, and

Figure 8, a diametrical section of a modified form of my closure.

As shown in the drawing, 10 represents a container in the form of a bottle including a body portion 11 and a neck portion 12 provided with 50 an external helical rib or screw thread 13. As illustrated the thread is continuous in form, but this is not essential.

55 The closure 15 for the container orifice includes

a cap 16 drawn up, in this case, from thin metal comprising a circular convex top 17 and a cylindrical side or skirt 18.

Mounted within the cap is a transversely split broad guide ring 20 of thin resilient metal whose end portions 21 overlap each other. In detail the ring includes an intermediate or body portion 22, a top edge portion 23 comprising an annular series of flutes 24, and an outwardly offset base portion 25 including a laterally extending shoulder 26 terminating in a depending flange 27.

In assembling the cap and ring an originally downwardly extending portion of the skirt is folded inwardly transversely of the flange 27 and against the inner face of the latter forming the lap 29 and fold 30 and forms a portion of the cap 16. The upper edge of the lap engages the lower face of the shoulder 26. During this folding step the upper edge of the ring was thrust against an intermediate portion of the lower face 20 of an originally flat circular filler disk 31, abutting against the cap top 17, with sufficient force to radially bend the annular marginal portion 32 of said disk at an incline relatively to the horizontal plane of the upper edge of the ring. The portion 32 cooperates with said upper edge of 25 the ring to increase the sealing efficiency of the structure. The disk is composed of pulp-board, cork, felt, or other suitable material.

The body portion of the guide ring includes a 30 guide element consisting of a helical rib or thread 34 adapted to slidably engage the rib or thread 13 of the container. The thread 34 as herein shown is of the interrupted type, but such type is not exclusive of a continuous thread, nor exclusive of 35 any other spirally disposed series of units adapted to contact with the thread 13.

The ring, which is of thin resilient metal, is sufficiently yielding to allow for the inequalities of surface or dimensions of the thread of the 40 container, or of the threads of various containers; the space between the body of the ring and the skirt of the cap facilitating such expansion.

The mutually overlapping flutes upon the end portions of the ring sufficiently interlock to prevent excessive expansion of the upper margin of the ring under unusual strain. The fluted character of the upper edge of the ring also extends the area of contact of the edge with the filler disk, which thus also contributes to the effective 45 retention of the disk in place.

The shell and enclosed ring are capable of 50 speedy mechanical formation and assemblage, and the completed closure shows no external disfigurement.

55

The structure of the cap 36, shown in Figure 8, differs from that shown in Figure 3 in that the top 37 is flat rather than convex, and the circular filler disk 38 is perfectly flat throughout its entire area.

5 I claim:—

1. A closure comprising a cap having top and skirt portions, a filler disk within the cap, and a split internal guide ring provided with overlapping ends and secured within the skirt portion with its upper edge bearing against the filler disk, said guide ring having its major portion including its upper edge portion spaced from the skirt portion of the cap for expansion relative thereto, the overlapping ends of the guide ring presenting a continuous upper edge to the disk.
- 10 2. In a closure of the character described, a cap including a top, a skirt, and an annular fold on the skirt, a filler disk contacting with the top, and an internal guide ring comprising a body portion spaced from the skirt, an offset lower portion engaged by the fold, and annularly disposed flutes upon the upper portion of the body engaging the disk.
- 15 3. In a closure of the character described, a cap including a top, a skirt, and a fold upon the skirt, a filler disk contacting with the top, and a transversely split guide ring including overlapping end portions, and comprising a body portion spaced from the skirt, an offset lower portion engaged by the fold, and flutes upon said overlapping portions engaging the disk.
- 20 4. In a closure of the character described, a cap including a convex top, a skirt, and an inwardly directed fold upon the bottom of the skirt, a filler disk provided with a downwardly inclined pe-

5 ripheral margin abutting against said top, a transversely split guide ring engaged at the lower edge by the fold and provided in its upper edge with annularly disposed flutes engaging an intermediate portion of the disk adjacent the inclined margin.

6 5. In a closure of the character described, a cap including a top and a skirt, a filler disk engaging the top, a guide ring secured within the skirt, and flutes at the top of the guide ring having the ends thereof engaging the disk.

10 6. A closure comprising a cap having top and skirt portions, and an internal guide ring secured to the skirt at its lower edge and having a body portion thereof spaced from the skirt portion and being transversely split with overlapping end portions arranged for yieldable expansion of said body portion relative to the skirt portion, said overlapping end portions having interfitting flutes therein arranged to interlock and prevent 15 excessive expansion of the ring.

15 7. A closure comprising a cap having top and skirt portions, the skirt portion having an annular internal fold at the lower edge thereof, a filler disk bearing against the under side of the top portion, and an internal guide ring having a threaded body portion spaced from the skirt portion, said guide ring having an offset lower portion engaged by the fold, and having overlapping ends arranged for yieldable expansion of the 20 body portion relative to the skirt portion without separation of the ends, the upper edge portion of the guide ring having upwardly extending flutes therein the ends of which engage an intermediate portion of the filler disk.

25 30 35 WILLIAM J. KEITH.
